UNITED STATES PATENT OFFICE.

RALEIGH W. TUCKER, OF BANDON, OREGON.

ARTIFICIAL ARM.

1,192,244.

Specification of Letters Patent. Patented July 25, 1916.

Application filed September 24, 1915. Serial No. 52,419.

To all whom it may concern:

Be it known that I, RALEIGH W. TUCKER, a citizen of the United States, residing at Bandon, in the county of Coos and State of Oregon, have invented new and useful Improvements in Artificial Arms, of which the following is a specification.

This invention relates to certain novel and useful improvements in artificial arms.

10 In carrying out the present invention, it is my purpose to provide an artificial arm wherein the gripping elements on the outer end of the arm may be quickly and conveniently opened and closed by the movement of the handless forearm equipped with my improved artificial arm, wherein the distance that the gripping elements open may be varied, and wherein the gripping elements may be turned relatively to the socket 20 of the arm and locked in the desired position.

It is also my purpose to improve and simplify the general construction of artificial arms and to provide an arm wherein the 25 component parts will be so arranged and correlated as to reduce the possibility of derangement to a minimum and at the same time enable access to be had to such parts for repairing, cleaning or the like.

30 With the above and other objects in view, the invention consists in the construction, combination and arrangement of parts hereinafter set forth in and falling within the scope of the claims.

35 In the accompanying drawings; Figure 1 is a perspective view showing my improved artificial arm in use. Fig. 2 is a longitudinal sectional view through the arm. Fig. 3 is a cross sectional view on the line 3—3 of Fig. 40 2. Fig. 4 is a similar view on the line 4—4 of Fig. 2. Fig. 5 is an enlarged fragmentary longitudinal sectional view taken at right angles to Fig. 2.

Referring now to the drawings in detail, 45 1 designates a socket adapted to receive the handless forearm and tapering downwardly from the inner end toward the outer end and split at its inner end for a portion of its length, the socket at the opposite sides of 50 the split portion being formed with eyelets 2 that receive a cord 3 whereby the socket may be laced tightly about the adjacent portion of the forearm. Encircling the outer end of the socket 1, that is, the relatively small end 55 thereof, is a metal annulus 4 having the

outer end thereof screw threaded as at 5 and threaded onto the outer end of the annulus 4 is, what I term a hollow wrist section 6 having the outer end thereof equipped with a cap 7 which may be either formed integral with the wrist section or detachably fastened thereto. Secured to the outer surface of the cap 7 and projecting outwardly therefrom is a hook section 8, while formed in the cap at one side of the hook section 8 is a slot 9 and projecting through the slot 9 and capable of swinging movement therein is a hook section 10 having the inner end thereof pivoted upon a pivot pin 11 arranged transversely of the wrist section 6. Formed integral with the inner end of the hook section 10 and projecting outwardly through a slot 12 formed in the side wall of the wrist section 6 is an operating arm 13 capable of swinging movement within the slot 12 to move the hook section 10 into and out of engagement with the hook section 8. The confronting edges of the hook sections 8 and 10 are preferably flattened so that when the sections are together they will present, 80 in effect, an integral hook. 14 designates a retractile spring having one end fastened to the arm 13 and the other extremity secured to the inner wall of the wrist section 8 and this spring acts to hold the movable hook section normally in engagement with the stationary hook section.

The wrist section 6 is capable of turning movement relatively to the socket so as to dispose the hook in any desired position relatively to the socket and of being locked in adjusted position. In the present instance, the locking means comprises a lever 15 pivoted between its ends upon a stud 16 carried by the side wall of the wrist section 6 and having one end projecting through a slot 17 formed in the side wall of the wrist section and the remaining end secured to one extremity of a retractile spring 18, such spring having the other end thereof fastened to the end cap of the wrist section. The outer end of the lever 15 is formed with an outwardly projecting shank 19 formed with a head 20. Formed in the outer threaded end of the annulus 4 and suitably spaced apart are notches 21 adapted to receive one edge of the lever 15 when the latter is actuated in one direction. Normally, the lever 15 is held in engagement with one or the other of the notches 21 under the action of the spring 105 110

- 18 and so holds the wrist section against turning movement relatively to the socket and maintains the hook in the desired position. When, however, it is desired to revolve the wrist section, the lever is swung about the stud 16 by the head 20 against the action of the spring 18, thereby disengaging the lever from the adjacent notch and permitting the wrist section to be revolved.
- 10 Formed in the side wall of the socket 1 is a longitudinally extending groove 22 opening onto the relatively small end of the socket within the annulus, and slidably mounted within this groove 22 is a bar 23 having one edge adjacent to the outer end formed with a series of notches 24 spaced apart appropriate distances longitudinally of the bar. Secured to the outer surface of the socket and covering the groove 22 therein is a 15 plate 25 formed of metal or other suitable material and provided with an elongated slot 26 adjacent to the inner end thereof and working within the slot 26 is a pin 27 carried by the adjacent portion of the bar 23 and pivoted upon the pin 27 between its ends is a lever 28 and pivotally connected to one end of the lever 28 is a yoke 29 and pivoted within the yoke 29 is one end of a link 30 capable of swinging movement at right 20 angles to the movement of the link, while pivotally secured to the remaining end of the link 30 is a yoke 31 capable of swinging movement at an angle to the movement of the link and connected to the outer end of 25 the operating arm 13. Pivotally connected to the inner end of the plate 25 is an arm 32 adapted to lie along side of that portion of the human arm between the shoulder and the elbow and having the inner end thereof 30 equipped with a strap 33 whereby the same may be fastened to the adjacent portion of the human arm. The remaining end of the lever 28 is connected through the agency of a link 34 with the arm 32. In the present 35 instance, the lever 28 and its associated parts and the slotted portion of the plate 25 are inclosed in a casing 35 of leather or other suitable material. Surrounding the annulus 4 and capable of rotary movement thereon 40 is a collar 36 equipped with a pin 37 projecting through a slot 38 formed in the annulus and adapted to engage in any one of the notches 24 in the bar 23 to hold the latter in the desired adjusted position.
- 45 39 designates a securing band adapted to encircle the human arm just above the elbow and coöperating with the socket 1 and strap 33 to maintain the artificial arm upon the human arm.
- 50 50 In practice, the artificial arm is secured to the human arm by the socket, the band 39 and the strap 33 and the arm 32 lies along side of that portion of the human arm between the shoulder and the elbow. In the 55 downward movement of the handless fore-

arm, the socket is similarly actuated and the lever 28 swung about the pin 27. In this swinging of the lever, the link 30 is projected forwardly with the effect to swing the actuating arm 13 against the action of the spring 14 to separate the hook sections. In the upward movement of the forearm, the artificial arm is similarly actuated and the direction of movement of the lever 28 reversed whereby the hook sections are drawn together and when drawn together 75 grasp any article between the same. The bar 23 is held against longitudinal movement within the groove 22 by means of the pin 37 on the collar 36 and when it is desired to vary the distance that the hook sections open, the collar 36 is rotated to disengage the pin 37 from the adjacent notch, and the bar moved longitudinally within the groove 22 to the desired position and 80 when the proper adjustment has been obtained the pin 37 on the collar 36 is engaged in the adjacent notch with the effect to maintain the bar 23 in adjusted position. When the bar is moved toward the outer end of 85 the socket, the throw of the arm 13 is shortened, while when the bar is moved in the opposite direction the throw of the arm 13 is lengthened, thereby enabling the hook sections to open any desired distance. 95

While I have herein shown and described one preferred form of my invention by way of illustration, I wish it to be understood that I do not limit or confine myself to the precise details of construction herein described and delineated, as modification and variation may be made within the scope of the claims without departing from the spirit of the invention. 100

I claim:

1. An artificial arm comprising a socket adapted to receive the handless forearm, means for securing said socket to the forearm, a wrist section on the outer end of said socket, a hook carried by the outer end of said wrist section and formed of two sections, one of which is capable of movement relatively to the other to open and closed positions, means operable by movement of the forearm for swinging said movable hook sections including a fulcrumed element, movable means upon which said element is fulcrumed, and means for moving said last-named means to change the fulcrum point of said element whereby the opening movement of said hook sections may be varied. 110
2. An artificial arm comprising a socket adapted to receive the handless forearm, an annulus on the outer end of said socket having the outer end thereof formed with outside notches, a wrist section mounted upon said annulus and capable of rotary movement thereon, and a lever pivoted within said wrist section and adapted to engage in any one of the notches in said annulus to 120
- 125
- 130

hold the wrist section against turning movement, and a hook carried by said wrist section.

3. An artificial arm comprising a socket 5 adapted to receive the handless forearm, an annulus on the outer end of said socket having the outer end thereof formed with notches, a wrist section mounted upon said annulus and capable of rotary movement 10 thereon, a lever pivoted within said wrist section and adapted to engage in any one of the notches in said annulus to hold the wrist section against turning movement, a hook carried by said wrist section, a spring within 15 said wrist section holding said lever normally in locking position, and means on said lever projecting through said wrist section whereby the lever may be swung against the action of the spring to release the wrist section. 20

4. An artificial arm comprising a socket adapted to receive the handless forearm, a wrist section on the outer end of said socket, a hook carried by the outer end of said wrist 25 section and formed of two sections, one of which is capable of movement relatively to the other to open and closed positions, a bar slidably mounted upon said socket, a lever pivoted between its ends upon said bar, means connected to one end of said lever and 30 operable in the movement of the forearm to swing the lever, and a connection between the remaining end of said lever and said movable hook section whereby the latter may be swung in the movement of the forearm. 35

5. An artificial arm comprising a socket

adapted to receive the handless forearm, a wrist section on the outer end of said socket, a hook carried by the outer end of said wrist 40 section and formed of two sections, one of which is capable of movement relatively to the other to open and closed positions, a bar slidably mounted upon said socket, a lever pivoted between its ends upon said bar, 45 means connected to one end of said lever and operable in the movement of the forearm to swing the lever, a connection between the remaining end of said lever and said movable hook section whereby the latter may be 50 swung in the movement of the forearm, said bar being capable of sliding movement to change the pivot point of said lever whereby the movement of said movable hook section may be varied, and means for locking said 55 bar in adjusted position.

6. An artificial arm comprising a socket adapted to receive the handless forearm, an annulus on the outer end of said socket having the outer end thereof formed with notches, a wrist section mounted upon said annulus and capable of turning movement 60 thereon, and a spring actuated lever pivoted within said wrist section and adapted to engage in any one of the notches in said annulus to hold the wrist section against turning movement. 65

In testimony whereof I affix my signature in presence of two witnesses.

RALEIGH W. TUCKER.
